Int. Cl. D26—05, 03; D14—01

U.S. Cl. D48—20 D

FIG. 1 is a top plan view of the combination speaker and spotlight showing my new design;

FIG. 2 is a front elevation view thereof, the rear elevation view being substantially identical; and

FIG. 3 is a bottom plan view thereof.

The cross-hatching is partially shown on the sphere for convenience of illustration, it being understood that the cross-hatching is uniformly continuous over the areas indicated.

I claim:

The ornamental design for a combination speaker and spotlight, as shown and described.
